Primary Examiner — Dana K Weiland(74) *Attorney, Agent, or Firm* — HP Inc. Patent Department(57) **CLAIM**

The ornamental design for a tablet, as shown and described.

DESCRIPTION

FIG. 1 is a top, front, right-side perspective view of a tablet in accordance with our new design;

FIG. 2 is a front elevational view of the tablet shown in FIG. 1;

FIG. 3 is a rear elevational view of the tablet shown in FIG. 1;

FIG. 4 is a left-side elevational view of the tablet shown in FIG. 1;

FIG. 5 is a right-side elevational view of the tablet shown in FIG. 1;

FIG. 6 is a top plan view of the tablet shown in FIG. 1;

FIG. 7 is a bottom plan view of the tablet shown in FIG. 1;

and,

FIG. 8 is a top, rear, right-side perspective view of the tablet shown in FIG. 1.

The broken lines immediately adjacent the shaded area represent the bounds of the claimed design while all other broken lines show portions of the tablet; the broken lines form no part of the claimed design.

1 Claim, 8 Drawing Sheets(56)
